US00D884165S

(12) **United States Design Patent** (10) Patent No.: **US D884,165 S**
(45) Date of Patent: **** May 12, 2020**

(54) **MOUNTING CRADLE**

(71) Applicant: **SPR Therapeutics, Inc.**, Cleveland, OH (US)
(72) Inventors: **Matthew G. deBock**, Morrisville, NC (US); **Joseph W. Boggs, II**, Chapel Hill, NC (US); **Matthew J. Wunzin**, Cleveland, OH (US); **Robert B. Strother, Jr.**, Willoughby Hills, OH (US); **Devin Sell**, Brecksville, OH (US); **Mark R. Stultz**, Maple Grove, MN (US); **Bradley A. Lewis**, Lyndhurst, OH (US)

(73) Assignee: **SPR Therapeutics, Inc.**, Cleveland, OH (US)

(**) Term: **15 Years**

(21) Appl. No.: **29/651,467**

(22) Filed: **Aug. 16, 2018**

(51) LOC (12) Cl. **24-02**

(52) U.S. Cl.

USPC **D24/128**; D14/263

(57) **CLAIM**

The ornamental design for a mounting cradle, as shown and described.

DESCRIPTION

FIG. 1 is a perspective view of a mounting cradle showing our new design;

FIG. 2 is a top view thereof;

FIG. 3 is a bottom view thereof;

FIG. 4 is a first side view thereof;

FIG. 5 is a second side view thereof;

FIG. 6 is a front view thereof; and,

FIG. 7 is a rear view thereof.

1 Claim, 5 Drawing Sheets
